UNITED STATES PATENT OFFICE.

EAVER LARSON, OF OGDEN, UTAH.

TIE-HOLDER.

1,371,176.

Specification of Letters Patent.

Patented Mar. 8, 1921.

Application filed December 22, 1919. Serial No. 346,439.

To all whom it may concern:

Be it known that I, EAVER LARSON, a citizen of the United States, residing at Ogden, in the county of Weber and State of Utah, have invented new and useful Improvements 5 in Tie-Holders, of which the following is a specification.

This invention relates to apparel, particularly to neckties, and has for its object the provision of a novel form and holder for a necktie of the four-in-hand type whereby the tie will not only be maintained in proper position to have a neat appearance but which also serves as means whereby the tie may be 15 secured upon a collar.

An important object is the provision of a made up tie of this character including a wire supporting frame so formed as to provide a rigid support within the knot of the tie, the tie being engaged between certain 20 elements of the support whereby to be retained in proper shape so that it will always have the proper appearance.

An additional object is the provision of a 25 device of this character which is formed from two lengths of wire cut and bent to shape and which will therefore be simple and inexpensive in manufacture, not likely to get out of order, and a general improvement in the art.

With the above and other objects and advantages in view, the invention consists in the details of construction to be hereinafter more fully described and claimed, and illustrated in the accompanying drawings in 35 which—

Figure 1 is a perspective view of my tie, Fig. 2 is a fragmentary rear elevation thereof, and

40 Fig. 3 is a perspective view of the form alone.

Referring more particularly to the drawings, the numeral 10 designates the curved portion of the device which is adapted for 45 engagement between the inner and outer portions of a turn down collar and 11 designates the tie supporting member. These two members are formed integral from a single length of wire which is bent to provide two 50 V-shaped members 12 having their vertices formed as loops 13 and secured together as by a metal sleeve 14 crimped thereabout. This length of wire is further bent to provide spaced curved arms 15 which form the 55 collar engaging portion 10 and one of which is a reflex bend of the other. This wire is

so bent that the tie supporting portion 11 is disposed inclined downwardly with respect to the collar engaging portion 10 so that the knot of the tie formed upon the support 11 60 will be held at the proper position with respect to the collar upon which the device is worn.

Secured to the wire at the bend formed at the juncture of the V-shaped members 12 65 with the curved arms 15 is another length of wire 16 which is bent into rectangular shape and coiled about each bend, as shown at 17. I also provide a thin spring wire 16^a having its ends secured as shown at 18. Intermediate 70 its ends, the wire 16^a is bent upon itself as shown and curved to provide a plurality of collar button engaging notches 20 which are provided so that the device may be used with collars of different styles. The wire 16^a 75 is of sufficient springiness to permit the collar button to be passed from one notch into another in effecting proper adjustment.

The tie is designated by the numeral 21 and this tie is formed upon the support 11 by 80 engaging one end between the V-shaped members 12, looping the tie about the support 11 to form the body, and then passing the free end of the tie through the last loop in the same manner as any four-in-hand tie is 85 tied. At various suitable points it is preferable that some of the convolutions of the tie be sewed together, as indicated at 21^a. The support 11, being rigid, will hold the knot of the tie in proper position. After 90 the tie is thus formed the device is applied by engaging the loop 20 upon the collar-button with the arms 15 disposed between the inner and outer portions of the collar. I also make use of a length of elastic 22 provided at its ends with hooks 23 engageable 95 within loops 24 formed at the extremities of the arms 15 and this elastic is disposed between the inner and outer portions of the collar at the back thereof. It is of course 100 understood that the device might also be used with a standing collar in which event the curved arms 15, with the exception of the loops at the extremities thereof, should be covered with the same fabric as that from 105 which the tie is formed.

From the foregoing description and a study of the drawing it will be apparent that I have thus provided an extremely simple and inexpensively made tie which 110 will properly hold its shape even after long use and which may be quickly and easily ap-

plied to a collar and retained in proper position thereon.

While I have shown and described the preferred embodiment of my invention, it is of course to be understood that I reserve the right to make such changes in the form, construction, and arrangement of parts as will not depart from the spirit of the invention or the scope of the subjoined claim.

Having thus described my invention I claim:—

15 A tie form of the character described comprising a curved collar engaging member and a tie supporting portion all formed from a length of wire bent intermediate its ends to provide a pair of downwardly converging V-shaped members having their

vertices looped and connected and constituting a downwardly and forwardly inclined 20 tie forming support and further bent to provide pairs of curved spaced arms engageable between the inner and outer portions of a collar, a length of wire disposed at the juncture of said V-shaped members with 25 said curved arms and coiled about the junc- tures whereby to provide a rectangular re- inforcing frame, and a separate length of wire secured at the two lower corners of 30 said reinforcing frame and bent upon it- self to provide spaced vertically extending arms outwardly curved at intervals to de- fine a plurality of notches selectively engage- able upon a collar button.

In testimony whereof I affix my signature. 35
EAVER LARSON.
